Inventor

John J. Roepke.

United States Patent Office.

JOHN J. ROEPPER, OF PHILADELPHIA, PENNSYLVANIA.

Letters Patent No. 98,301, dated December 28, 1869.

BASE-BURNING STOVE.

The Schedule referred to in these Letters Patent and making part of the same.

I, JOHN J. ROEPPER, of the city of Philadelphia, in the State of Pennsylvania, have invented certain Improvements in Magazine-Stoves, of which the following is a specification.

Nature and Objects of the Invention.

My invention relates to the combination, with a magazine-stove, of a direct-draught flue outside of the magazine, so as to form a large, open communication, regulated by a valve or damper between the hot space around the outside of the said magazine and above the top surface of the incandescent fuel in the fire-chamber; the object of my invention being to dispense with the objectionable draught through the magazine, by closing it, and affording not only a more effective one outside of the latter, but an important additional heat-radiator at the back part of the stove.

Description of the Accompanying Drawings.

Figure 1 is a vertical central section (from front to rear) of a magazine-stove for a fire-place, embodying my invention.

Figure 2 is a plan view of the top plate of the same.

General Description.

A is the magazine, supported within the fire-chamber in the usual manner.

B, the incandescent-fuel space between the lower end of A and the usual grate b'.

b'', the hot space around the magazine A and above the incandescent-fuel line.

C, the large direct-draught flue, communicating with the space b'', and the usual chimney-flue D, and e', its valve or damper.

E is the air-warming and distributing chamber, forming the upper end of the stove, and

a', the feed-channel of the magazine, forming a passage-way for the feed through the chamber E.

The magazine A and the incandescent-fuel space B, are constructed and arranged, in relation to each other, in the usual manner, with this difference, *i. e.*, in my im-

provement the top of the magazine A is entirely closed, excepting the feed-channel a', by a solid plate, which forms also the bottom plate e', of the air-warming and distributing chamber E, so that there cannot occur any draught or current of air upward through the said magazine to the chimney-flue D, and consequently the tendency of the coal in the magazine to become ignited, as heretofore, is entirely prevented, without preventing its becoming heated; whilst the direct draught required at times, and especially in starting the fire in the stove, is amply provided for by the flue C, which is made as large in diameter as its position between the usual indirect flues (not shown in the drawings) will permit, thus giving a large heat-radiating surface, and a direct-draught flue between the hot space b'' and the chimney-flue D, the said draught being either controlled or entirely stopped, by means of the sliding valve or damper e', the handle e'', of which, projects conveniently in front of the stove, through the top plate e''.

Between the top plate e'' and the plate e', there is transversely arranged, a fixed upright plate, e'', which completely separates the flues from the chamber E; and the plate e', extending directly and entirely over the whole of the heated fuel, and the surrounding spaces in the fire-chamber, becomes heated and warms the air in the chamber E, and also warms the top plate e'', which, being perforated by numerous small holes, 4 4, there is consequently a constant warming and distribution of fresh air by means of the said chamber E.

Claim.

I claim, as my invention—

In combination with a magazine-stove, the direct flue C, the chimney-flue D, and the space b'', outside of the magazine A, substantially as and for the purposes hereinbefore set forth.

JOHN J. ROEPPER.
